United States Patent Office

Des. 210,645

Patented Mar. 26, 1968

210,645

KEY CASE

Kenneth D. Kraus, 322 W. 72nd St.,
New York, N.Y. 10023

Filed June 21, 1965, Ser. No. 85,806

Term of patent 14 years

(Cl. D87—3)

Fig. 1.

Fig. 2.

Fig. 3.

FIG. 1 is a front perspective view of a key case, showing my new design, in closed condition;

FIG. 2 is a perspective view thereof in open condition; and

FIG. 3 is a rear perspective view thereof.

The essential features of my design are shown in full lines.

I claim:

The ornamental design for a key case, as shown and described.
